[57] CLAIM

The ornamental design for a satellite reception locating device, as shown and described.

DESCRIPTION

FIG. 1 is a front elevational view of a satellite reception locating device showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a top, front and side perspective view of a second embodiment of my new design; and

FIG. 8 is a top, front and side perspective view of a third embodiment of my new design.

FIG. 1

FIG. 2

FIG. 3

FIG. 4

FIG. 5

FIG. 6

FIG. 7

FIG. 8
